MERCURY SWITCH

Alrik Civer Lindström, Stockholm, Sweden

Application August 26, 1939, Serial No. 292,146
In Sweden August 30, 1938

9 Claims. (Cl. 200—152)

This invention relates to improvements in mercury switches and the like. The invention has reference particularly to mercury switches which consist of a closed rotatably mounted receptacle in which there are two mercury masses each in connection with an electrode. These mercury masses may be united with each other or separated from each other by tilting the receptacle from one end position to the other end position, whereby the electric circuit connected to said electrodes is closed and interrupted, respectively.

One of the objects of the invention is to provide a mercury switch of very simple form and construction, which is cheap in its manufacture and which has the advantage that the dimensions in an axial direction are reduced to a minimum.

Another feature of the invention relates to the method of fitting the electrodes which are of metal to the receptacle which is made of insulating material. This new method renders it possible to make the spaces within the receptacle gas-tight so that no oxidation of the surface of the mercury can occur.

According to the invention, the receptacle has an inner space for one mercury mass and an outer space for the other mercury mass, which outer space surrounds the inner space. Preferably, these spaces are annular, while the inner or centre space thereof may be cylindrical. These spaces are so arranged relatively to each other and relative the axis of rotation of the receptacle that the geometrical axes coincide with each other or are at least parallel with each other.

Other objects and uses of the invention will appear from a detailed description of the same which consists in the features of construction and combinations of parts hereinafter described and claimed.

In the drawing:

Fig. 1 is a transverse sectional view of one embodiment of the invention on the line I—I of Fig. 2.

Fig. 2 is a longitudinal sectional view taken on the line II—II of Fig. 1.

Fig. 3 is a section through a modified construction of a part belonging to the switch.

Fig. 4 is a vertical section through another embodiment of the switch, the section being taken along line IV—IV in Fig. 6.

Fig. 5 is a similar section along line V—V in Fig. 6.

Fig. 6 is a section along line VI—VI in Fig. 4.

Fig. 7 is a partial section through a detail of the switch. The cover shown in section in Fig. 6 has been left out in Figs. 4 and 5.

The embodiment illustrated in Figs. 1 and 2 concerns a mercury switch which comprises a base plate 2 on which are mounted two brackets 4 and 6 adapted to support the mercury receptacle in a rotatable manner and which at the same time serve as leads to carry the current. 10 A protecting cover 8 fixed to the base plate has an opening 10 through which extends an arm or a handle 12 serving for actuating the switch. The tilting of the receptacle is limited by the ends of the opening, so that the receptacle may be moved from one end position shown by dotted lines at the left hand side to the other end position shown by dotted lines at the right hand side.

The receptacle proper of the switch consists 20 of a body of insulating material having the form of a short cylinder which is hollow and externally is provided at the end surfaces with metal caps or lids 14 and 16 serving as electrodes. These metal caps and the central body 25 are surrounded at the circumference and also at the end surfaces with a cover 18 which preferably consists of artificial resin, such as "Bakelite," so that this cover may be applied by pouring or pressing the raw material onto the 30 central body. This cover 18 has a projection 12 by means of which the switch may be tilted as desired. The metal caps 14 and 16 which preferably consist of iron or non-corrosive steel, inasmuch as these metals are more suitable for 35 cooperation with mercury, have central projections 20, 22 which extend through the cover 18 and serve as journals for the receptacle. In order to improve the electrical contact the projections 20 and 22 are preferably provided with 40 minor caps 24 and 26 of brass or similar material of good conductivity which rest by means of flanges against the brackets 4 and 6 and serve as journals in the holes 4' and 6' in said brackets.

45 The central body of insulating material consists preferably of refractory porcelain or other ceramic material. It has the form of two short coaxial tubes 28 and 30 which are united with each other at both ends by means of end walls 32 and 34. The two tube-like parts 28 and 30 together with the end wall 32 are made in one piece before burning the porcelain body, while the end wall 34 is made by itself. During burning this wall 34 will be sintered together with 50 the three parts 28, 30 and 32, so that the joint

disappears and the body is constituted by a coherent mass. It is quite possible to place the joint on the other side of the body, so that the parts 28 and 30 are made integral with the end wall 34 before the burning, and it is further possible to divide the insulating body in any other manner. For instance, it may be mounted together by using three or more parts. According to another method the insulating body may be made by first forming and burning each part and then join the parts together by glazing. 10

In the insulating body made according to one of the methods just mentioned there will be formed two spaces, or an outer annular space 38 and an inner cylindrical space 36. The axes of these spaces preferably coincide with each other and even with the axis of rotation of the receptacle, but it is also possible to carry out the insulating body in such manner that the axes only are parallel with each other. The end walls 32 and 34 have openings or channels 39 and 40 by means of which the two spaces are in communication with the spaces between the external surfaces of the end walls and the metal caps 14 and 16. The opening or channel 39 effects communication between the external annular space 38 and the space adjacent the cap 16, while the opening or channel 40 brings about communication between the central space 36 and the space adjacent the cap 14. It is possible to alter the arrangement of the channels as illustrated in Fig. 3, so that the external annular space 38 has communication to the left and the central space 36 has communication to the right. 30

The receptacle is filled with mercury up to 35 more than half of its volume. The one mercury mass therefore fills the space 36, the channel 40 and the greater part of the space between the end wall and the cap 14, and for this reason it always makes electric contacts with this cap 14. The second mercury mass is in the space 38, the channel 39 and the greater part of the space between the end wall and the cap 16, so that the latter is always in electric contact with the mercury. 40 In the tubular part 30 of the insulating body there is a radially directed channel 42 which connects the central space 36 with the outer space 38 and by means of which the two mercury masses are united with each other when the receptacle is tilted in a conuterclockwise direction from the position shown with full lines in Fig. 2 to the left hand position indicated by dotted lines. 45 In the opposite end position, that is to say the right hand position shown with dotted lines, the extreme outer end of the channel 42 is entirely above the surface 48 of the mercury, so that then the electric contact is interrupted. Preferably, the channel 42 is situated along a line passing through the centre of the receptacle and forming an angle of approximately 45° with the horizontal when the receptacle occupies the position shown in Fig. 2 with full lines. This arrangement brings about the advantage that the switch without any alteration whatever may be mounted on a horizontal or on a vertical support. If the switch is turned, for instance, 90° around its axis so that the base plate 2 occupies a vertical position, that is to say, when the drawing is turned an angle of 90° in its own plane, the surface of the mercury will occupy the position as indicated by the dotted line 44. Even in this case the two mercury masses may be united with each other and separated from each other by swinging the handle 42 from one end position to the other end position. 70

The channels 39 and 40 are in communication 75

with the lower part of the pertaining space in the insulating body, and in all positions of the switch during its use they are always under the free mercury surface and preferably also under the horizontal plane passing through the axis of the receptacle. Furthermore, preferably they are situated diametrically opposite to the channel 42, that is to say, along a line passing through the centre of the receptacle and forming an angle of approximately 45° with the horizontal when the switch occupies the intermediate position shown with full lines in Fig. 2.

By this arrangement it is possible in a similar manner as just mentioned in connection with the channel 42 to mount the switch as well vertically as also horizontally, inasmuch as the channels 39 and 40 in no case will be above the horizontal plane passing through the axis of the receptacle. 15

The spaces between the end walls and the metal caps are always separated from the spaces 38 and 36 by a liquid seal, and contaminations which may have flaked off from the metal caps and thus may collect on the surfaces 48 will not be transferred by the movements which the receptacle carries out during the use of the switch to the interior of the receptacle in order to there make the interruption of the arc difficult. For the same purpose serves also the form of the receptacle which is symmetrical with respect to the axis of rotation and which, therefore, does not permit the transportation of mercury from one space to the other when actuating the switch. 20

It is to be noted that the spaces between the metal caps and the outer walls of the receptacle will never be free of mercury but they are always almost completely filled with mercury. If, for instance, a superpressure should arise within the receptacle on account of interruption of the arc, there will be no danger that an appreciable quantity of mercury will be pressed into the said spaces and thereafter be transported back in opposite direction. Further, the arc or mercury vapor arising thereby has no possibility to be thrust against the metal caps and to damage the same or to increase the contact resistance between the caps and the mercury. 30

The embodiment described above may be subjected to various changes without affecting the scope of the invention. One of such modified embodiments is shown in Figs. 4 to 7 and will now be described.

This second embodiment differs from the one first described by the fact that the receptacle which in the first case consists of the central body 28, 30, 32, 34 and the outer cover 18 is made in one piece in the second embodiment. In making this receptacle the method employed is similar as when making the first embodiment, that is to say, one part 51 provided with recesses and the lid 52 pertaining thereto are made separately of porcelain and will be sintered together in burning the same or they may be united with each other by glazing. The main part 51 has a projection 53 which serves as handle in order to be able to actuate the switch, and it has a second projection 54 arranged approximately diametrically opposite to the first one and cooperating with a leaf spring 55 for the purpose of limiting the tilting movement of the receptacle. With this in view, this spring 55 has two shoulders 56 and 57, and the spring is inserted with its free ends into slots 58 and 59 in the base plate 2. In a manner similar to that shown in Fig. 1 the switch is surrounded by a protecting cover 8 having an opening 10. The main part 51

has a cylindrical inner space 60 and an annular outer space 61. The inner or central space 60 is in communication by means of a radial channel 62 with the outer annular space 61, and this latter is in communication by means of a radial channel 63 with the space at the right end surface of the part 51.

The lid 52 has an opening 64 through which mercury is filled into the receptacle when making the switch.

Both end surfaces of this central body are covered by metal caps 65 and 66. These caps have centrally an annular flange 67 so that an opening is provided through which mercury can be filled into the receptacle. Upon this mercury having been poured in, the said opening will be closed by means of a minor cap 70 having its end surface directed towards the receptacle. The closing of this opening will be carried out, for instance, in the following manner. On the outer circumferential surface of this cap will be applied some artificial resin, such as "Bakelite," and a heated mandrel is inserted into the cap. By means of this mandrel the cap is inserted into the opening of the metal cap 65, the resin is thereby heated and in this way the small cap will be cemented to the flanges. As external protection and in order to obtain a better journal a third cap 71 for instance of brass, is fitted over the outside of the flanges and soldered thereto. The big caps 65 and 66 and also the minor cap 70 inserted into the openings of the former consist of iron or of non-corrosive steel, inasmuch as this material is most suitable for the cooperation with mercury.

The gas-tight fixing of the metal caps to the central body will be carried out in the embodiment shown in Fig. 1 at the same time as the outer cover 18 of insulating material is applied thereto.

In the second embodiment the metal caps are fastened as shown in Fig. 7. The two end surfaces of the parts 51 and 52 have annular recesses 72' and 73. In correspondence to these recesses the metal caps 65 and 66 have an annular flange 74 and 75. At first a thermoplastic medium, such as "Bakelite" 71 is inserted into the recesses 72 and 73 and then the caps are mounted on the "Bakelite" by the application of heat. By this means the metal caps will be sealed to the central body. In order to fix these metal caps also mechanically there is used a non-thermoplastic medium, such as porcelain cement 79 which is applied to the parts at the corner formed between the circumference of the metal caps and the outer wall of the recesses.

In this second embodiment of the invention the channels 62 and 63 are arranged and situated in a manner similar to the first embodiment, that is to say, when the receptacle occupies an intermediate position the central line of these channels forms an angle of approximately 45° with the horizontal.

Several illustrative embodiments of the principles of the present invention have been described. Since various matters of combination, arrangement, structure and design may be modified without departing from the inventive features, it is not intended to limit the invention to such

matters except so far as set forth in the appended claims.

What I claim is:

1. A tiltable mercury switch comprising, a receptacle mounted for rocking movement between two end positions, two electrodes on said receptacle, a mercury mass in contact with said electrodes in said receptacle, an insulating wall between each of the electrodes and a space in the receptacle, a further insulating wall extending between the first-mentioned walls and dividing the space in the receptacle into an inner space and an outer space surrounding the inner space, said last-mentioned dividing wall having an aperture therein adapted on the rocking movement of the receptacle to be located above the mercury level in one end position of the switch and underneath the mercury level in the other position of the switch, each of the first-mentioned walls having an aperture therein located underneath the mercury level in both positions of the switch and underneath a horizontal plane passing through the axis of rotation of the receptacle providing communication between one electrode and said inner space and between the other electrode and said outer space, and means holding the electrodes adjacent the ends of the receptacle.
2. A tiltable mercury switch as claimed in claim 1, in which the inner and the outer spaces are arranged in the same plane and at right angles to the axis of rotation of the receptacle.
3. A tiltable mercury switch as claimed in claim 1, in which the outer space is annular and the central space is cylindrical.
4. A tiltable mercury switch as claimed in claim 1, in which the axes of the two spaces and the axis of the receptacle are parallel with respect to each other.
5. A tiltable mercury switch as claimed in claim 1, in which the receptacle consists of a short hollow cylinder of insulating material, and the cylinder being provided at the end surface with metal caps serving as the electrodes.
6. A tiltable mercury switch as claimed in claim 1, in which the receptacle consists of two coaxial tubes which are united at the end surfaces by means of end walls, one end wall having an opening which is in communication with the inner space and the other end wall has an opening which is in communication with the outer annular space.
7. A tiltable mercury switch as claimed in claim 1, in which a handle integral with the receptacle is provided for rotating the receptacle.
8. A tiltable mercury switch as claimed in claim 1, in which the aperture providing communication between the two spaces is situated along a line which forms an angle of approximately 45° with the horizontal when the receptacle occupies a central position intermediate two end positions.
9. A tiltable mercury switch as claimed in claim 1, in which the apertures providing communication between the electrodes and the spaces in the receptacle are arranged along a line which forms an angle of approximately 45° with the horizontal when the receptacle occupies a central position intermediate two end positions.

ALRIK CIVER LINDSTRÖM.
